UNITED STATES PATENT OFFICE

2,166,521

SHOE POLISHING DEVICE

William B. Derbyshire, Philadelphia, Pa.

Application November 27, 1937, Serial No. 176,785

2 Claims. (Cl. 15—266)

My invention relates to a new and useful shoe polishing device and has for one of its objects to provide an exceedingly simple, inexpensive and effective article of this character whereby 5 a person may readily and easily polish his or her own shoes in an efficient manner without undue exertion.

Another object of the invention is to locate guides on a suitable support or base in positions 10 that permit the use of a polishing cloth in a way to expeditiously polish either or both the front and rear portions of a shoe as well as practically all of the side surfaces.

Another object of this invention is to removably 15 mount the rear guides on the support or base whereby the device may be stored in a small space.

Another object of the present invention is to form 20 sockets in the support or base to receive the rear guides and to mount bushings in said sockets to prevent excessive wear due to frequent intermittent use of said rear guides.

A further object of the invention is to provide 25 the forward or side guides with inset attaching ends the formation of which produce shoulders to properly position said guides relative to other parts of the device and form loops to regulate the lateral positions of the polishing cloth.

With the above and other objects in view, this 30 invention consists of the details of construction and combination of elements hereinafter set forth and then designated by the claims.

In order that those skilled in the art to which 35 this invention appertains may understand how to make and use the same, I will describe its construction, referring to the accompanying drawing forming a part hereof, in which:

Fig. 1 is a perspective view of the shoe polishing 40 device embodying my invention showing a shoe in the position for polishing the forward part thereof.

Fig. 2 is a side elevation thereof with portions 45 broken away and illustrated in section to show details of construction.

Fig. 3 is a top plan view of the same showing how the rear part of a shoe can be polished.

In carrying out my invention as herein embodied 50 5 represents a support or base which may be produced from a piece of wood such as a section of board and desirably cleats 6 or their equivalents are fixed crosswise to the underside of the board and actually form a part of the base 5.

A pair of spaced, horizontal forward or side

guides 7 are mounted on top of the base longitudinally thereof. Each of said forward or side guides is produced from a rod or large wire having both ends curved inward to provide loops 8, the underside of which function as shoulders 9 to position the bar of the guide the proper and desired distance above the top face of the base. A threaded terminal 10 projects from each loop 8 through the base 5 and has a nut 11 threaded thereon and engaging the underneath 10 face of the base. All of the nuts are embedded or housed in the cleats 6.

In the base 5 to the rear of the forward or side guides 7 and preferably in line therewith are formed sockets 12 which may have bushings 13 in them to prevent the sockets from becoming unduly worn and enlarged. Rear vertical guides 14, round in cross section, are removably mounted in the sockets and said rear guides should be of sufficient height to reach the top 20 of a shoe which is to be polished and in fact it is advisable that such rear guides extend above the top of a shoe when the latter is in a position to be polished. The ends of the rear guides should be rounded or dome shaped so that when in use the ends which are uppermost will be smooth and free of any sharp corners which might have a tendency to cut or otherwise damage a polishing cloth.

Between the forward and side guides 7 and on the base is mounted a foot rest 15 which extends from a location adjacent the front ends of said forward or side guides 7 to a position a considerable distance back of the rear guides 14. This foot rest should be narrow so that the 30 side edges of a shoe to be polished extend beyond the sides of said foot rest, Fig. 3, and also said foot rest should be of sufficient height to project above the forward or side guides 7 to give proper elevation of a shoe relative to said forward or side guides for a purpose that will be apparent from the following explanation.

To polish the forward part or toe end of a shoe, the person wearing the shoe places his or her foot upon the foot rest 15 with the polishing cloth 16 passing under both of the forward or side guides 7 and over the shoe as illustrated in Fig. 1. By grasping both ends of said polishing cloth the wearer of the shoe may reciprocate a portion of the cloth across or over the shoe by 45 alternately moving the ends of the cloth generally up and down. To operate upon a large surface of the forward portion of the shoe, including the toe, instep and front side elements, the polishing cloth may be slid back and forth

along the guides 7 longitudinally thereof. When it is desired to polish the rear part or heel end of the shoe the wearer places the foot in a position on the foot rest so that said rear part of the shoe projects well back between the rear guides 14 as suggested by the illustration in Fig. 3 with the polishing cloth 16a, which may be the same cloth as used for polishing the forward part of the shoe or another cloth, passing around the rear of the shoe and the forward faces of the guides 14. The further back the shoe is positioned, the greater amount of shoe surface that will be engaged by the polishing cloth and therefore the more surface that will be operated upon by one manipulation of said polishing cloth. With the shoe and cloth in position as shown in Fig. 3 the ends are grasped and alternately moved backward and forward, either endwise or sidewise relative to the base, causing a portion of the cloth to reciprocate over the rear part of the shoe to polish the same.

Of course I do not wish to be limited to the exact details of construction herein shown and described as these may be varied within the scope of the appended claims without departing from the spirit of my invention.

Having thus described my invention, what I claim as new and useful is:

1. In a shoe polisher, a base, a pair of side guides each produced from a round rod and fashioned to provide a bar, an inturned loop at each end and a threaded terminal projecting downwardly from each loop, the terminals of said guides passing through the base with shoulders formed by the undersides of the loop engaging the top surface of the base, nuts screwed onto said terminals and engaging the underside of the base, and a foot rest mounted on said base between said guides with its top surface above the guides.

2. A shoe polisher comprising a base with a foot rest thereon, a pair of side guides mounted in parallel spaced relation on top of the base with one guide on each side of the foot rest, each of said side guides consisting of a bar, an inturned loop at each end of the bar forming a shoulder to rest against the top surface of the base and threaded terminals projecting downwardly from the loops through the base, nuts screwed onto said terminals and engaging the underside of the base, and cleats mounted on the bottom of the base crosswise thereof and housing the nuts.

WILLIAM B. DERBYSHIRE.
